(57) **CLAIM**

The ornamental design for a solar-powered electronic device housing, as shown and described.

DESCRIPTION

FIG. 1 is a top, front, left side perspective view of an embodiment of a solar-powered electronic device housing; FIG. 2 is a bottom, rear, right side perspective view thereof; FIG. 3 is a left side elevation view thereof; FIG. 4 is a front elevation view thereof; FIG. 5 is a right side elevation view thereof; FIG. 6 is a rear elevation view thereof; and, FIG. 7 is a top plan view thereof.

The evenly spaced broken lines and areas within them depict portions of the solar-powered electronic device housing that form no part of the claimed design.
